PANTS HANGER

Cyril James Hunt, Morrisville, Pa.

Application May 2, 1938, Serial No. 205,615

2 Claims. (Cl. 223—63)

The invention relates to a garment hanger and more particularly to pants hangers.

The primary object of the invention is the provision of a hanger of this character, wherein through the use of a pair thereof trousers can be hung and the leg portions thereof maintained creased while the said trousers are in hanging position and in this way avoiding the wrinkling of the leg portions of said trousers, maintaining the fabric smooth, the hanger being readily manipulated for the fitting thereof to the garment for the hanging of the same or the removal of such hanger when the garment is to be worn.

Another object of the invention is the provision of a hanger of this character, wherein the same is susceptible of having the parts thereof separated from each other and certain of the parts folded or brought to a contracted condition for the easy storing of the hanger when not in use and also assuring of its occupying the least possible space when stored.

A further object of the invention is the provision of a hanger of this character, wherein the clamping arms thereof are of a foldable character and on extending thereof will be susceptible of folding in one direction only so that they may be held in a position to clamp the leg portion of trousers so that the latter can be hung and the leg portions maintained in a creased or pressed condition.

A further object of the invention is the provision of a hanger of this character, wherein the construction thereof is novel in its entirety, being possessed of few parts and is susceptible of spreading and contracting action for the fitting thereof in the leg portion of trousers of different sizes and when so fitted will permit of the hanging of the trousers and the maintaining of the leg portions in a pressed or creased condition.

A still further object of the invention is the provision of a hanger of this character, which is simple in its construction, thoroughly reliable and efficient in operation, convenient for the handling thereof and the hanging of trousers, strong, durable and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary perspective view of trousers having the leg portions fitted with a pair

of hangers, constructed in accordance with the invention, for the hanging of the trousers and the stretching of the leg portions for maintaining the same pressed or creased.

Figure 2 is an enlarged elevation of the hanger removed from the trousers.

Figure 3 is a vertical sectional view showing the clamping arms in the extended position and latched against folding with relation to each other in one direction.

Figure 4 is an exploded fragmentary perspective view of parts of the hanger.

Figure 5 is a sectional view on the line 5—5 of Figure 2.

Similar reference characters indicate corresponding parts throughout the several views in the drawing.

Referring to the drawing in detail, A designates generally a pants or trousers hanger constituting the present invention, being two of these employed for the hanging of the pants or trousers, the pair being indicated generally at 10 and engaged in the leg portions of the pants or trousers, these being indicated at 11 in Figure 1 of the drawing.

The hanger A comprises a spring wire supporting member including a centrally disposed spring coil 12 and downwardly extended legs 13, respectively, the latter being created from the end portions of the wire and are disposed at opposite sides of the said coil 12 effecting therethrough the resilient legs and are of equal length. The legs 13 are formed at their terminals with headed attaching studs 14, these extending laterally from the said legs 13 and are separably engageable with relatively movable bars 15 arranged side by side, each of which has provided therein an elongated keyhole-shaped slot 16, the enlarged open end 17 thereof allowing for the removable engagement of the headed stud 14 in said slot 16 while said bars are also provided with the openings 18 for the insertion of the studs 14 therethrough to allow engagement of the same in the slot 16 and in this manner the said bars 15 are slidably connected together and also de-

tachably connected with the legs 13 at the studs 14 thereof so that the bars 15 are slidably related to each other for the spreading and contracting of the same. The legs 13 under tension of the coil 12 are disposed in crossed relation to each other when engaged with the bars 15 and in this manner the latter will be placed under tension through the tensioning action of the coil 12 upon said legs and such bars in this manner are moved into sliding relation to each other.

Swingingly connected to the bars 15 at the outer ends thereof are pairs of foldable stretcher arms 19, these being pivoted together and also pivoted to the bars 15 by a pivot 20 and in this manner the said arms are susceptible of swinging relative to each other and to the bars 15.

One of the arms has cut and bent therefrom adjacent to the pivot 20 and at one longer side edge thereof an offset stop tongue 21 for engagement in a keeper notch 22, being shouldered at 23 and formed in the other arm of the pair in the path of the stop 21 so that the arms of each pair are susceptible of swinging outwardly away from the bar 15 to which said arms are pivotally connected but will be prevented from swinging reversely or inwardly only to a degree bringing the arms in longitudinal alignment with each other. The arms 19 of each pair when in alignment with each other are latched in this position so that when the hanger is inserted in the leg portion 11 of trousers or pants, these pairs of arms 19 will engage the said leg portion and through the tension of the coil 12 causes a stretching activity upon the leg portion for maintaining it creased or pressed in that the arms 19 have contact with the crease line of the leg portion at the interior thereof. By this engagement of the hanger A, two of the same being employed at one time, the trousers or pants can be hung from a support, for example, a nail 24 and such pants or trousers at the leg portion thereof will be maintained in a pressed condition with the fabric smooth and stretched preserving the crease in the leg portion.

In fitting the hanger to the pants or trousers within each leg portion 11 thereof, an operator grasps the legs at 13 of the supporting member and by pressing upon these legs the bars 15 will slide inwardly with relation to each other, the pairs of arms 19 being extended into alignment of one arm with the other of each pair. The hanger can now be readily inserted in the cuff end of the leg portion 11 and when the sup-

porting member is released the bars 15 spread relative to each other causing the pairs of arms 19 to engage the leg portion 11 and through the use of the two hangers, as shown in Figure 1 of the drawing, the pants or trousers can be hung as before set forth.

When the hanger is not in use, the studs 14 of the legs 13 of the supporting member can be separated from the bars 15 and the arms 19 pivoted thereto swung outwardly for the folding of these arms and in this manner the hanger in its disassembled condition can be readily stored in the least possible space.

Each hanger is adaptable for fitting the leg portion of trousers or pants of different sizes and when said hanger is slightly contracted in the manner as before stated, the same can be introduced into the leg portion of the trousers or pants and on the spreading of the hanger through the tension of the coil 12 the said hanger will hold the trousers or pants leg, being a stretching action thereon and in this manner maintaining the leg portion creased and thus avoiding the wrinkling of the same when the trousers or pants are hung.

What is claimed is:

1. A hanger of the character described comprising relatively movable bars, a supporting element separably connected with and coupling the bars together, means included with said supporting member for exerting spreading action on said bars, and arms pivoted to the said bars and movable to fixed alignment with each other.

2. A hanger of the character described comprising a supporting member having a spring coil and legs extending at opposite sides thereof in cross relation to each other, bars detachably coupled with the said legs and with each other and tensioned by the spring coil, foldable arms swingingly supported on said bars, and means for holding the arms in alignment with each other at opposite sides of said supporting member.

CYRIL JAMES HUNT.
